[57] CLAIM

The ornamental design for a vehicle seat, as shown and described.

DESCRIPTION

FIG. 1 is a top, right perspective view of a vehicle seat showing my new design;

FIG. 2 is a top plan view thereof;

FIG. 3 is a front elevation view thereof;

FIG. 4 is a bottom plan view thereof;

FIG. 5 is a rear elevation view thereof;

FIG. 6 is a right elevation view thereof. The right side of the vehicle seat is a mirror image of the left side except that it has a recessed region for a seat belt near the top thereof;

FIG. 7 is a left elevation view thereof; and,

FIG. 8 is a left side sectional elevation view taken along section lines 8—8 of FIG. 3. This sectional view provides further details of the design which are not as apparent from the other views.

Stippling is intended to indicate portions of the design formed of a softer material than the portions shown with shading lines.
